UNITED STATES PATENT OFFICE.

OTTOKAR HOFMANN, OF ARGENTINE, KANSAS, ASSIGNOR TO THE UNITED ZINC AND CHEMICAL COMPANY, OF KANSAS CITY, MISSOURI, A CORPORATION OF NEW JERSEY.

ROASTING-FURNACE.

SPECIFICATION forming part of Letters Patent No. 768,748, dated August 30, 1904.
Application filed August 29, 1903. Serial No. 171,238. (No model.)

To all whom it may concern:

Be it known that I, OTTOKAR HOFMANN, a citizen of the United States, residing at Argentine, in the county of Wyandotte and State of Kansas, have invented certain new and useful Improvements in Roasting-Furnaces, of which the following is a specification.

My invention relates to that class of roasting furnaces known as the "McDougall" type. The furnaces of this class are so constructed that in a cylindrical steel or iron shell which is lined with bricks roasting-shelves are arranged one above the other, through the center of which a hollow shaft is inserted. To this shaft rakes or stirring-arms are attached corresponding to the different shelves, by means of which the ore is not only stirred, but also moved so that it gradually drops from one shelf to the other until it is automatically discharged from the last shelf. These furnaces are mostly used for roasting highly-sulfurated ore, like iron pyrites, where the roasting is principally performed for the purpose of utilizing the produced sulfuric-acid gas for the manufacture of sulfuric acid, or for roasting zinc-blende ore for the double purpose of using the gas to make sulfuric acid and the cinders for the manufacture of spelter. When used for zinc ore, more roasting-shelves are required, of which some of the lower ones have to be muffled to permit the application of additional heat by means of a special fire without allowing the fuel combustion-gases to mix with the roasting-gases. As the central shaft of the furnace, as well as the stirring-arms which are attached to the former are made of iron and iron is readily attacked by sulfur when red-hot and also warps when exposed to higher heat, it is apparent that these costly iron parts will be of short duration if not properly cooled. The stirring-arms are the parts most exposed to the destroying influence, and the operator is obliged to renew them from time to time, and it is of great importance that this should be done quickly without cooling down the furnace, as this would be connected with an interruption

of the work, and consequently with great loss of time and money. It is therefore desirable in constructing such furnaces, first, to provide for good cooling of the central shaft; second, to provide for an efficient cooling of the stirring-arms, and, third, to construct the attachment of the stirring-arms to the central shaft in such a way as to permit a quick and easy withdrawing and replacing of the defective arm.

My invention relates principally to improvements in the apparatus indicated or outlined in the above-enumerated three points, and I believe it to constitute a decided advance on the art of constructing roasting-furnaces.

In the accompanying drawings, Figure 1 represents a vertical section through the center of the furnace, and Fig. 2 a top view of the same. Fig. 3 is a cross-section, and Fig. 4 a vertical section, through the tubular shaft S, showing the sockets for the stirring-arms. Fig. 5 is an outside view, and Fig. 6 an inside view, illustrating the sockets for the stirring-arms. Fig. 7 is an enlarged plan, and Fig. 8 an enlarged sectional view, of the upper end of the tubular shaft; and Fig. 9 is an enlargement of a portion of Fig. 8.

The furnace as represented is arranged for roasting ores like zinc-blende, which require additional heat for completing the roast, and is therefore provided with more roasting-shelves A A A than are usually found in a furnace of that type, of which the three lower ones can receive additional heat by the three inserted fire-flue chambers B B B. The central hollow shaft S is provided with a number of recesses C C, two of which always correspond in their vertical location with the location of one of the roasting-shelves. They are placed diametrically opposite and serve for the insertion of the stirring-arms W. Their position, however, in relation to the different roasting-shelves is so that the arms in every succeeding shelf are horizontally at right angles with the arms of the preceding one, so that the ore dropping from one shelf to the

other does not strike the rake. The recesses or openings C C are cone-shaped and extend a little into the hollow of the shaft and are formed by a ring-shaped swelling of the iron or boss around the opening in the shaft. They form neither pockets nor passages extending laterally through the shaft; but they are merely recesses open on both ends, so that through them the inside of the hollow shaft is in communication with the roasting-chambers. In each of these recesses is inserted a cone-shaped sleeve P, which is fastened to the central shaft by means of bolts. These sleeves form the sockets for the stirring-arms. They are cone-shaped, with the narrow end inside the shaft. In the upper and lower side of these cones is cut a groove V longitudinally, Figs. 3 to 6. These grooves commence a little distance inside, so as to leave the opening on the outside of the shaft a perfect circle. The stirring-arms W are hollow and closed at one end; but the end which is destined to be inserted is open and shaped on the outside like a cone and fits into the sleeve P. To the end of this cone are attached two lugs V', Fig. 8, the position of which is ninety degrees away from the center line of the stirring-blades U of the arm. To insert the arm, the same is brought in such position that the lugs point up and down, while the stirring-blades are horizontal. By a forward movement of the stirring-arm into the sleeve the lugs move through the grooves until they pass over the inner edge of the sleeve. Then a quarter-turn is given to the arm, by which the stirring-blades are brought to point down and are therefore in the proper position for work. Part of the inner edge of the cone-shaped sleeve and corresponding to the two lugs is shaped after the line of a screw, as shown at M in Figs. 3 and 4. If, therefore, the quarter-turn is given to the arm, the lug traveling on the line of a screw will pull in the stirring-arm, thus producing a fit of the arm in the sleeve preventing roaster-gas from entering the shaft. When the quarter-turn is made, the lugs come to rest against the shoulders L, formed by the screw-shaped cut in the sleeve, so that by the resistance the latter are held rigidly against the shoulders L. The joint just described may be termed a "bayonet-joint." To withdraw the arm for the purpose of replacing the same by a new one, all that is needed is to give the arm a quarter-turn in the opposite direction and to pull the same out of the sleeve.

As illustrated by Fig. 3, the sleeve P is provided with two flanges, which are curved to comply with the rounding of the shaft and fit in a depression in the latter corresponding in shape with the flanges, so that the flanges do not project above the surface of the shaft. These sleeves are fastened to the shaft by

means of bolts X; but in order to permit the replacement of an old sleeve by a new one in case this should be required without cooling the furnace the bolts are of a peculiar shape one end of each bolt being threaded, while the other is provided with two wings X', Figs. 6 and 8. The bolt-holes have two slots diametrically placed and corresponding to the wings of the bolt. If a new sleeve is placed into the recess of the shaft while the furnace is hot, the nut is screwed onto the threaded end of the bolt and placed into a long-handled socket-wrench and the bolt inserted into the bolt-hole of the sleeve so that the wings pass through the slots. When inserted and turned, the wings strike a projection inside, so that by further turning only the nut turns and not the bolt, so that the former can be screwed tight.

In the center of the hollow shaft is inserted an iron gas-pipe E, which is provided with pipe-fittings which permit the connection of smaller pipes F with the vertical pipe E. These connections are so arranged that the pipes F project out into the furnace through the center of each two opposite recesses. The foot end of the vertical pipe E is closed and provided with a square iron block G, which fits into a square hole in the foot end of the shaft. This is done to keep the pipes always in proper position and to prevent any independent movement of the same. At the top the pipe is also held in position by the socket H. At this end the vertical pipe is provided with a stuffing-box N, by which it is connected with the stationary pipe I, which in turn is connected with the air-pipe of a blower. Near its foot and outside the furnace the hollow shaft is provided with openings K, which serve for the admission of air into the shaft and to give access to the foot of the pipe E in case of repair. The upper end of the shaft enters a stack (not shown) to increase the draft and to remove the heated air. To facilitate the connecting of the horizontal pipes F with the vertical pipe E while the furnace is hot, I use the bayonet-joint illustrated by Fig. 9. The end of the pipe F is screwed into a round casting Z with two flat wings O. The fittings T of the vertical pipe E have a recess with two grooves O'. Into this the casting end of the pipe F is inserted, and by giving a quarter-turn a tight and rigid fit is given to the pipe.

To start operation, the stirring-arms are slipped over the pipes F, inserted in the conical sleeve, and brought in position by giving the same a quarter-turn. Then the blower is started. The air is forced through the branch pipes F into the stirring-arms at their farthest ends, returns through the full length of the arms, and leaves them to enter the hollow shaft, where it unites with the upward current of air which enters at the foot of the

shaft through the openings K. By this arrangement an efficient cooling of the stirring-arms, as well as of the central shaft, is obtained, which of course lengthens the life of the iron parts of the furnace and enables me to construct furnaces of a larger diameter, and consequently of larger working capacity; but the compressed air is not merely used as a cooling agent for shaft and stirrers. It is used also as a lute to prevent the loss of gas through the central shaft. As the central shaft is connected with a stack to increase the draft through it, while the roasting-shelves are connected by flues with the Glover tower and lead-chambers of an acid factory, we will find that the air in the shaft is under a much greater suction strain than the gas of the roasting-shelves. Assuming that some of the stirring-arms do not fit tight in the sleeves, some gas will be drawn into the shaft and will be lost. In using compressed air as a cooling agent we can regulate the influx of air so as to produce an equilibrium between the suction in the shaft and the suction in the furnace, thus preventing any leakage through defective places. The same effect cannot be produced by the use of a damper in the stack of the shaft, because this would reduce the volume of air passing through the shaft to such a degree that the cooling effect would be insignificant, which would be detrimental to the life of the shaft.

In the roasting-shelves Nos. 2 and 3 the most heat is developed, and consequently in course of time the upper part of the shaft will first give out. In such a case if the shaft is one piece of casting it would necessitate the withdrawal of the old shaft and the replacing of the same by a new one, which is not only connected with considerable difficulties, but is also costly. To avoid this, I construct, preferably, the shaft in three sections, as illustrated by Fig. 1.

Having described my invention, what I claim as new, and desire to secure by Letters Patent, is—

1. In a roasting-furnace of the class described, a hollow shaft provided with openings or recesses, and separate cone-shaped sleeves arranged in said recesses and secured to said shaft and adapted to receive the stirring-arms.

2. In a roasting-furnace of the class described, the combination of a hollow shaft provided with openings at the roasting-shelves, sleeves fitting said openings and provided with flanges, and bolts for connecting the flanges to the shaft, said bolts being provided with nuts at one end and with wings at the opposite end adapted to interlock with the shaft.

3. In a roasting-furnace of the class described, the combination of a hollow shaft having recesses at the several roasting-shelves

opening into said shaft, cone-shaped sleeves fitting in said recesses and suitably connected to said shaft, and stirring-arms fitting said sleeves, said stirring-arms having lugs and said sleeves having grooves with which said lugs interlock, said grooves commencing at a point inside the sleeve, whereby the outer end of each cone-shaped opening is circular, insuring a close fit of the stirring-arm.

4. In a roasting-furnace, the combination of a hollow shaft with recesses at each roasting-shelf, extending into the shaft, said recesses being open at both ends, cone-shaped sleeves inserted in said recesses and bolted or otherwise fastened to said hollow shaft and adapted to be withdrawn and replaced while the furnace is hot, said sleeves having one or more grooves commencing at a point inside the sleeve and extending longitudinally through the balance of the sleeve, part of the inner edge of the sleeve shaped after the line of a screw and provided with a stopping-shoulder, and stirring-arms fitting said sleeves, substantially as described.

5. In a roasting-furnace, the combination of a hollow shaft having recesses, and sleeves with spiral inner edges, with hollow stirring-arms inserted in said sleeves, one end of each arm being shaped to fit into its sleeve and provided with one or more lugs placed ninety degrees off from the central line of the stirring-blades, said lug or lugs coöoperating with the spiral edge of the sleeve to pull the arm tight into the sleeve, substantially as described.

6. In a roasting-furnace, the combination of a hollow shaft and hollow stirring-arms thereon, with an air-pipe, said air-pipe passing centrally through the hollow shaft and being closed at the bottom and connected at top and bottom to the hollow shaft so that pipe and shaft will rotate together without changing their relative positions, and being provided with branch pipes, said branch air-pipes being provided at one end with cast-iron lugs forming bayonet-joints with recesses in fittings of the central air-pipe, said central vertical air-pipe to be connected by suitable means with the stationary pipe of a blowing-machine, substantially as described.

7. In a roasting-furnace of the class described, the combination of a hollow vertical shaft, stirring-arms removably connected to said shaft by bayonet-joints, an air-pipe within said vertical shaft, and branch air-pipes within the stirring-arms, said branch pipes being detachably connected to said main air-pipe by bayonet-joints.

8. In a roasting-furnace of the class described, the combination of a series of shelves or roasting-hearths, a vertical hollow shaft, hollow stirring-arms connected to said shaft, a vertical air-pipe centrally located in said shaft, and branch air-pipes located in said

stirring-arms, said hollow shaft having openings at top and bottom to provide for a draft therethrough, and said branch air-pipes being arranged to discharge into the outer ends of said stirring-arms, the air so discharged passing through the stirring-arms to the vertical hollow shaft.

In testimony whereof I have signed my name to this specification in the presence of two subscribing witnesses.

OTTOKAR HOFMANN.
